UNITED STATES PATENT OFFICE

KENNETH M. WILKINS, OF WAUKEGAN, ILLINOIS

ELECTRIC TROLLEY HEAD

Application filed March 6, 1929. Serial No. 344,661.

This invention relates to overhead trolley contacts in which electric contact is made with an overhead trolley wire or conductor by a contact shoe or slider, an example of which constitutes the subject matter of the Hough and Shultis Patent No. 1,491,403 dated August 22, 1924. And the present improvement has for its various objects:

To provide a structural formation and combination of the contact shoe or slider and its carrying head whereby a strong attachment of the parts and one capable of ready disassembly is attained, and with which an efficient electrical contact between the parts is provided.

To provide a like formation and combination of the carrying head of the shoe or slider and the trolley pole whereby a maximum electrical conducting capacity in the parts is attained with a view to prevent undue heating of the trolley pole, due to the natural electrical resistance of the metal of said pole, in its use on trains carrying heavy loads, necessitating in consequence a larger supply of electro-motive force to the motors of such trains, all as will hereinafter more fully appear.

In the accompanying drawings:

Fig. 1, is a side elevation illustrating the general arrangement of parts in the present invention.

Fig. 2, is an end elevation of the carrying head and contact shoe or slider mounted in said head.

Fig. 3, is a side elevation of the contact shoe or slider.

Fig. 4, is an end view of the same.

Fig. 5, is a longitudinal section of the carrying head and contact shoe or slider.

Fig. 6, is a transverse section of same, on line 6—6, Fig. 5.

Like reference numerals indicate like parts in the several views.

The trolley pole 1 used in the present structure is of the usual wrought iron tubular formation and constitutes a part of the circuit of the electro-motive force used in propelling the vehicle. Under ordinary conditions such pole formation offers but little

resistance to the passage of such electro-motive force. With the use of such trolley pole formation in the circuit of the electro-motive force for heavily loaded cars or train of cars, requiring a maximum supply of electro-motive force to the driving motors, such form of trolley pole owing to its low electric conductivity offers an objectionable amount of resistance to the passage of the electric current so that in many cases the material of the pole is brought to a red heat owing to such defective nature in a trolley pole of the such defective nature in a trolley pole of the described formation in an effective and economical manner, the present invention provides a provision as follows:

A high conductive wire or cable 2 of copper or like metal is arranged in the interior of the tubular trolley pole 1, with the upper end of said wire or cable electrically connected by brazing or like connecting means to the metal of the trolley pole in close relation to the hereinafter described trolley pole harp and carrying head of the contact shoe or slider of the present structure. At its lower end the wire or cable 2 is connected to, or may form an integral part of the supply conductor to the driving motor of the vehicle.

In the construction shown, the upper portion 3 of the trolley harp is of the usual forked formation with the carrying head 4 of the contact shoe or slider 5 of such construction pivotally mounted between the forked members of the harp by the usual transverse pivot bolt 6, as shown.

The carrying head 4 above referred to, is of the usual elongated form, the upper portion of which is formed with the usual outwardly flared longitudinal side cheeks 7, and between said cheeks the head is formed with the usual longitudinal recess the side walls 8 of which incline towards each other, so as to have substantial holding engagement with a complementary formation of the side walls of the contact shoe or slider 5 when in place in said recess.

In the present improvement a longitudinally extending slot 9 is formed centrally in

the carrying head 4 with such slot opening into the above described receiving recess, with the portions thus separated capable of being forcibly drawn together by transverse bolts 5 to firmly clamp and hold the contact shoe or slider 5 in place in the receiving recess of the carrying head. In the preferred construction shown the under face of the contact shoe or slider 5 is formed with transverse 10 grooves 11 adapted to receive portions of the shanks of the aforesaid clamping bolts 10, with a view to prevent independent longitudinal shift of the shoe or slider 5 in its receiving recess of the carrying head 4.

15 At its midlength the carrying head 4 is formed with a depending tubular hub 12, the transverse orifice of which carries a lining or bushing 13, for bearing contact on the aforesaid pivot bolt 6 of the structure, while 20 at one end the carrying head is provided with a downwardly curved extension or horn 14, to the lower end of which the hereinafter described flexible conductor 15 is fixedly attached at one end by rivets 16 or like fastening means.

25 The flexible conductor 15 above referred to is of a loop form and is arranged between the forked members 3 of the trolley harp, and at the end opposite to its attachment to the aforesaid extension or horn 14 of the carrying head 4, has electrical attachment to the trolley pole 1 immediately adjacent to the point of connection of the aforesaid wire or cable 2 to said pole.

30 With such construction effective conducting capacity is provided in the trolley portion of the system, with the resistance of the trolley pole, when used solely as a conducting medium, to the passage of a heavy electric 35 current, is eliminated, and with a prevention of the ordinary effect of bringing the metal of the trolley pole to a red heat, an ordinary occurrence in overhead trolleys of the present type when used in the passage of a heavier type than usual electric current supply.

40 The contact shoe or slider 5 above referred to is formed with a concave upper or contact face, with the ends of such face having a downward curve, while the under surface of 45 the slider is of a flat form, adapted for ready fit with a complementary flat formation of the heretofore described receiving recess of the carrying head 4.

Having thus fully described my invention 50 what I claim, is:—

1. In a trolley structure of the type described, the combination of a tubular trolley pole having attaching means adjacent to its upper end, a forked harp secured to the upper 55 end of said pole, a carrying head and contact member mounted in said harp, a conducting wire or cable arranged in the bore of the trolley pole and fixedly connected at its upper end to the aforesaid attaching means, and a 60 flexible conductor connected at one end to the 65

aforesaid carrying head and at the other end to the aforesaid attaching means.

2. In a trolley structure of the type described, the combination of a tubular trolley pole having attaching means adjacent to its upper end, a forked harp secured to the upper 70 end of said pole, a carrying head and contact member mounted in said harp and having a depending horn at one end, a conducting wire or cable arranged in the bore of the trolley pole and fixedly connected at its upper 75 end to the aforesaid attaching means, and a flexible conductor connected at one end to the depending horn aforesaid, and fixedly connected at its other end to the aforesaid attaching means.

3. In a trolley contact head of the type herein described, the combination of a carrying head formed with flaring side wings, with a longitudinal receiving recess having 85 bevelled side walls between said side wings, and with a central longitudinal slot opening into said recess, a contact shoe or slider fitting said receiving recess, and transverse bolts passing through the carrying head for drawing the portions of said head separated by the aforesaid longitudinal slot into holding contact with the contact shoe or slider.

4. In a trolley contact head of the type herein described, the combination of a carrying head formed with flaring side wings, with a longitudinal receiving recess having 90 bevelled side walls between said side wings, and with a central longitudinal slot opening into said recess, a contact shoe or slider fitting 95 said receiving recess, and transverse bolts passing through the carrying head for drawing the portions of said head separated by the aforesaid longitudinal slot into holding contact with the contact shoe or slider, said contact shoe or slider having transverse 100 grooves in its under side for engagement with portions of the shanks of the transverse bolts aforesaid.

105 In testimony whereof I affix my signature. 110
KENNETH M. WILKINS.
